UNITED STATES PATENT OFFICE.

ARNAULD J. RICARD, OF SLATER, MISSOURI.

FOUNTAIN-BRUSH.

1,165,208.

Specification of Letters Patent. Patented Dec. 21, 1915.

Application filed August 2, 1915. Serial No. 43,329.

To all whom it may concern:

Be it known that I, ARNAULD J. RICARD, a citizen of the United States, residing at Slater, in the county of Saline and State of Missouri, have invented a new and useful Fountain-Brush; and I do hereby declare the following to be a full, clear, and exact description of the invention, such as will enable others skilled in the art to which it appertains to make and use the same.

This invention relates to the art of scrubbing and the like, and particularly to an improved fountain brush particularly adapted for use by stenographers, jewelers, locksmiths and printers, a stenographer using the same for cleaning the type bars and the like, while the jewelers use the same for cleaning small parts of clocks and the like, and the locksmith for cleaning parts of locks.

One of the features of the invention is the provision of improved means for controlling the cleaning fluid from the fountain to the brush.

In practical fields the details of construction may necessitate alterations, falling within the scope of what is claimed.

The invention comprises further features and combination of parts, as hereinafter set forth, shown in the drawings and claimed.

In the drawings:—Figure 1 is a view in perspective of the improved brush constructed in accordance with the invention. Fig. 2 is a longitudinal sectional view on line 2—2 of Fig. 1. Fig. 3 is a sectional view on line 3—3 of Fig. 1. Fig. 4 is an enlarged detail view in section showing the means for controlling the fluid from the fountain to the brush. Fig. 5 is a detail view of a portion of the handle which constitutes the fountain, showing the disk valve disassembled therefrom. Fig. 6 is a transverse view on line 6—6 of Fig. 2.

Referring to the drawings, 1 designates the wood portion of the brush consisting of two sections 2 and 3, the section 3 being secured to the section 2 as at 4 in any suitable manner. The bristles or the hairs 5 may be secured to the section 3 in the usual manner. The section 2 is constructed with a chamber 6, whereas the section 3 is provided with a plurality of apertures or openings 7 through which cleaning fluid, as it enters the chamber 6, may pass, so as to wet or moisten the bristles or hair of the brush, when using the same. This brush may be

used by printers for washing small type forms, as well as being used in the mailing galley rooms of newspapers. The section 2 has a threaded opening 8 leading into the chamber 6, and into this threaded opening an elbow 9 (which is hollow) is threaded. The elbow has a portion of its wall thickened, as shown at 10, and extending through this thick portion is an opening or passage 11, which is offset from the fluid passage 12. The end 13 of the elbow extends within the flared flange 14 of the contracted closed end 15 of the handle 16, which is hollow, thereby constituting a fountain for the cleaning fluid 17. A suitable packing 18 is arranged where the end 13 of the elbow and the closed end of the handle 16 engage, thereby preventing leakage of the fluid. Interposed between the closed end 15 and where the flange 14 flares a disk valve 19 is disposed. The disk valve has an opening 21, which is designed to be thrown into and out of the registration with the opening 22 of the closed end 15 and the passage 12, so as to control the fluid in its flow from the fountain to the passage 12.

The fountain handle where the flange 14 is formed is cut away to form a slot 23, in which the lug 24 moves in one direction or the other. When the lug 24 is moved in the direction of the arrow a, in Fig. 6 and limited by the end wall 26 of the slot or recess 23, the opening 21 will register with the opening 22 of the closed end 15, to permit the cleaning fluid to pass through the passage 12. A bolt 27 extends through the closed end 15 of the handle 16 and through the center of the disk valve (forming a pivot for the valve) and through the opening or passage 11 of the thickened wall 10, and is provided with a nut 28 so as to hold the parts securely together. A coil spring 29 is mounted upon the bolt and in the passage or opening 11, and has one end secured at 30 in any suitable manner to the wall of the passage 11, the other end secured at 31 to the disk valve 19, so as to hold the opening 21 normally out of registration with the opening 22. When the disk valve is rotated, it is accomplished against the action of the spring 29. It will be noted that the bolt not only forms a support for the spring 29, and a centering pivot for the disk valve, but also holds the handle 16 to the elbow 9. ~~It is~~ ^{also} ~~possible~~ ^{possible} screening 32 is arranged in the chamber 6 over the apertures or opening 7, so as to

retard the flow of the cleaning fluid to a certain degree. A screening 33 is also secured between the threaded end of the elbow and the flange 34, to also retard the flow of 5 the fluid. Adjacent the rear end of the handle 16 a reduced threaded part 35 is provided, to which the closure 36 is threaded. This closure 36 has a very small orifice 37, to allow air to enter the handle, so that the 10 fluid therein will flow through the passage of the elbow.

The invention having been set forth, what is claimed as new and useful is:

1. In combination, a brush having a chamber in the wood portion thereof and provided with perforations to permit fluid to pass therethrough to the bristles, an elbow threaded into the wood portion of the brush in communication with the chamber, a fountain handle connected to the other end of the elbow, a bolt connecting the handle to the elbow, and a spring tensioned disk valve mounted on the bolt between the handle and the elbow.
2. In combination, a brush having a chamber in the wood portion thereof and provided with perforations to permit fluid to pass therethrough to the bristles, an elbow threaded into the wood portion of the brush 20 in communication with the chamber, a fountain handle connected to the other end of the elbow, a bolt connecting the handle to the elbow, and a spring tensioned disk valve mounted on the bolt between the handle and 30 the elbow, the end of the handle which is connected to the elbow having an opening registering with the passage through the elbow, the disk valve having an opening held normally out of registration with the 35 opening of the handle by the spring means of the valve.
3. In combination, a brush having a chamber in the wood portion thereof and provided with perforations to permit fluid to 40 pass therethrough to the bristles, an elbow threaded into the wood portion of the brush 45

in communication with the chamber, a fountain handle connected to the other end of the elbow, a bolt connecting the handle to the elbow, and a spring tensioned disk valve 50 mounted on the bolt between the handle and the elbow, the end of the handle which is connected to the elbow having an opening registering with the passage through the elbow, the disk valve having an opening 55 held normally out of registration with the opening of the handle by the spring means of the valve, and screening in the chambers to retard the flow of the fluid.

4. In combination, a fountain handle having a closed end provided with a small opening, an elbow connected to the closed end of the handle and having a passage registering with the opening of the closed end, said elbow having an opening disposed 60 to one side of the passage in the elbow, a disk valve mounted between the closed end of the handle and the adjacent end of the elbow and provided with an opening designed to be moved into and out of registration 65 with the passage of the elbow and the opening of the closed end, a bolt extending through the closed end centrally and through the offset opening and provided with means to hold said parts together, the bolt acting 70 as a centering pivot for the disk valve, a spring on the bolt in the offset opening connected to the valve to normally hold the valve with its opening out of registration 75 with the opening of the closed end, and a brush having a chamber in the wood portion thereof connected to the other end of the elbow and provided with apertures of communication between the chambers and the 80 bristles of the brush.

In testimony whereof I have signed my name to this specification in the presence of two subscribing witnesses.

ARNAULD J. RICARD.
